G. F. NEWTON.
TIGHTENER FOR FORM CLAMPS.
APPLICATION FILED NOV. 29, 1915.

1,255,210.

Patented Feb. 5, 1918.

UNITED STATES PATENT OFFICE.

GEORGE F. NEWTON, OF INDEPENDENCE, MISSOURI, ASSIGNOR TO WM. M. BUNTING, OF KANSAS CITY, MISSOURI.

TIGHTENER FOR FORM-CLAMPS.

1,255,210.

Specification of Letters Patent. Patented Feb. 5, 1918.

Application filed November 29, 1915. Serial No. 64,039.

To all whom it may concern:

Be it known that I, GEORGE F. NEWTON, a citizen of the United States, residing at Independence, in the county of Jackson and 5 State of Missouri, have invented certain new and useful Improvements in Tighteners for Form-Clamps; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

My invention relates to a tightener for form clamps or the like, and has for its principal object to provide a simple and efficient mechanism for drawing the members 20 of a form together, so that they may be held in close relation, during the pouring and setting of material within the form.

In accomplishing this object I have provided improved details of structure, the 25 preferred forms of which are illustrated in the accompanying drawings, wherein:—

Figure I is a perspective view of part of a form for molding a vertical column showing one of the clamp rods and the tightening 30 mechanism.

Fig. II is a longitudinal section of the clamp and tightening mechanism, showing a part of the form.

Fig. III is a detail perspective view of 35 the ratchet wrench that forms part of the tightening mechanism.

Fig. IV is a side view of the wrench, with one of the jaws removed to illustrate the ratchet.

Fig. V is an enlarged elevation of the 40 ratchet, showing the reversible pawl in different positions in full and dotted lines.

Referring more in detail to the drawings:—

45 1 designates a part of a column form, here shown to consist of longitudinally arranged boards, and cross bars 2. Extending through a cross bar 2 and lying along one side of the form is a tightening rod 3, 50 which extends through the ends of the cross

bar and carries a collar 4, having an enlarged flange 5 bearing against the outer face of the cross bar.

The interior of the collar is of sufficient 55 diameter to receive rods of substantial size and preferably contains the upstanding ribs 7—8 which are spaced apart to form a recess 9 therebetween, into which a rod that is contained within the collar may be forced, by engagement of the end of a set screw 10 60 that is carried in the collar opposite the ribs 7—8, and is operable from the exterior of the collar.

In practice the form is set up and the 65 tightening rod located along one side thereof and extended through the cross bars 2, the projection of the ends of the rod being sufficient to carry the tightening mechanism. The collars are located loosely on the rods and forced against the faces of the cross 70 bars until the forms are sufficiently tight, when the collars may be anchored to the rod by means of the set screws 10 and the tightening mechanism removed.

The tightening mechanism for performing 75 the function described preferably consists of a sleeve 12, having exterior screw threads 13, and having a head flange 15 at its outer end, comprising spaced ears 16—17, between which a cam 18 is pivotally 80 mounted.

The cam 18 comprises a head 19 that is projected into the channel of the sleeve 12 to engage the rod 3, and has a V-groove 20 therein within which the rod may lie in 85 order to afford a more efficient contact of the cam against the rod. In order to force the cam automatically to contact with the rod I provide a spring 22 which is anchored on one of the sleeve ears and engages a tail 90 23 on the cam, from beneath, in order to urge the cam toward its rod engaging position, movement of the cam toward said position being limited however by the pins 24—24' on the cam head, that are adapted 95 for engaging the sleeve bead, to obviate excessive movement of the cam.

In order to adapt the device for use with different sized rods, I also preferably provide the head 15 with a set screw 25 which 100

is located directly opposite the cam and may be raised or lowered to form a seat for the rod 3, so that when the cam is in functional position the rod will be gripped between the 5 cam and the end of the set screw.

The ratchet wrench which comprises an element of a tightening mechanism comprises a barrel 27 that is threaded onto the sleeve 13 and has a head 28 that is adapted 10 to bear against the outer end of the collar 4, and is preferably provided with a nut socket 29, within which an ordinary nut may seat so that the wrench may be used for purposes other than that directly limited to 15 the form mechanism. The base of the nut socket 29 comprises an aperture 30 through which a clamp may be projected and guided. The barrel 27 is provided, about midway its length, with a ring flange 31, having ratchet 20 teeth 32 thereon, and rotatably mounted on the barrel, at opposite sides of the ring flange, are handle members 33-34, the arm 33 being preferably extended to form a handle 35 and the arm 34 being secured to 25 the member 33 by any suitable means, both parts being cut away to form the socket 36 within which the ratchet may lie when the parts are assembled.

Pivottally mounted on a pin 38 that extends 30 between the arms 33-34 is a double headed pawl 39, the head 40 and 41 of which are adapted for respective but separate engagement with the ratchet at opposite sides of the center line, the base of the 35 pawl having the flat faces 42-43 adapted for engaging a flat spring 44 that is mounted in the wrench handle in order to yieldingly hold the ratchet pawl in place, so that when one of the flat faces is in engagement 40 with the spring, a relative ratchet head will engage the pawl and when the other flat face is in engagement with the spring, the opposite pawl head will engage the ratchet, the direction of operative movement 45 of the wrench being thereby determined by the position of the pawl.

The mounting of the spring 44 preferably comprises transversely slotted ears 46-47 on the wrench handle, into which the spring 50 44 may be projected, the said spring being preferably provided with corrugations 49 at one end, whereby that end of the spring may be securely locked within the handle slot while the other end is free to slide within its 55 slot and thereby effect the operative spring movement.

In using the device and assuming that it is to be used on a vertical column, the column form members are first set up, and 60 assembled, and the rod 3 extended through the projected ends of the cross bars, so that the bars will lie against the sides of the form. Collars 4 are then slipped on over

the ends of the rods 3 until they bear against the outer faces of the cross bars and one of the collars fixed in position by tightening the set screw 10 against the rod 3. The tightening device is then placed on the opposite end of the rod by slipping the sleeve 13, carrying the tightening wrench, over the 65 end of the rod until it bears against the loose collar 4. The wrench barrel is then moved inwardly by manipulation of the handle 35 to force the head 28 of the barrel against the outer ends of the collar 4, this inward 70 movement of the wrench barrel relieving the cam head, so that the spring 22 may trip the head until it engages the rod and clamps thereon. Further movement of the wrench barrel forces the head 28 against the end of 75 the collar and pushes outwardly on the sleeve 13, outward movement of said sleeve being restrained however by the engagement of the cam with the rod, so that the collar 4 is forced inwardly against the form bar and 80 85 the form tightened by such movement.

As soon as the form has been sufficiently tightened, the set screw 10 on the collar is forced against the rod to lock the collar firmly in place and hold the form to its 90 tightening position. The tightener may then be removed by reversing the action of the wrench and moving same outwardly along the sleeve until the outer end of the wrench barrel again engages the cam and 95 rocks to move the head from the rod, when the tightener may be slipped off the rod and used in another location.

It is apparent that by providing the wrench with the double pawl, the pawl will 100 slip in one direction and hold in the other when set for one position, and that the action is reversed when the pawl is set for the other position, so that the wrench may be used for either right or left hand work, and 105 that by providing the wrench barrel with the end socket 29 the wrench may be used for purposes other than that for which it is particularly adapted.

Having thus described my invention, 110 what I claim as new therein, and desire to secure by Letters-Patent, is:—

1. The combination with a sleeve, of a cam carried by said sleeve, means for normally urging the cam to functional position, 115 a barrel threaded onto said sleeve and adapted for engaging the cam to move same to non-functional position against the tension of the yielding means, a handle rotatably mounted on the barrel, and a pawl on 120 said handle adapted for operatively connecting the handle with the barrel.

2. The combination with a sleeve, having an exterior threaded portion, of a head on 125 said sleeve provided with spaced ears, a cam pivotally mounted between said ears and

having a head at one end and a tail at the opposite end, a spring engaging said tail and urging the cam head toward functional position, a barrel threaded onto the sleeve 5 and adapted for engaging the cam tail to rock the same to non-functional position, a ratchet ring on the barrel, a wrench rota-

tably mounted on the barrel and anchored thereto by said ratchet ring, and a pawl pivotally mounted on the wrench member 10 and adapted for engaging said ratchet ring.

In testimony whereof I affix my signature.

GEORGE F. NEWTON.
